UNITED STATES PATENT OFFICE.

CHARLES R. SPENCER, OF ATLANTA, GEORGIA, ASSIGNEE OF ONE-THIRD TO WALTER W. STRONG AND ONE-THIRD TO ROLIN S. SASNETT, BOTH OF ATLANTA, GEORGIA.

ROTARY ENGINE-VALVE.

1,111,680.

Specification of Letters Patent. Patented Sept. 22, 1914.

Application filed February 7, 1913. Serial No. 746,976.

To all whom it may concern:

Be it known that I, CHARLES R. SPENCER, a citizen of the United States, residing at Atlanta, in the county of Fulton and State of Georgia, have invented certain new and useful Improvements in Rotary Engine-Valves; and I do hereby declare the following to be a full, clear, and exact description of the invention, such as will enable others skilled in the art to which it appertains to make and use the same.

This invention comprehends improvements in engines and relates more particularly to rotary valves for internal combustion engines of the four cycle type.

The primary object of the invention resides in the provision of a rotary valve comprising a hollow cylindrical body open at each end and divided longitudinally into two compartments, the body being provided with novelly shaped intake and exhaust passages communicating with the respective compartments.

Another object of the invention resides in the provision of a valve of this nature which will open the intake and exhaust ports quickly and which will gradually close the same in such a manner as to permit the incoming and outgoing gases to always take the shortest path.

The invention also aims to generally improve valves of this nature, to render them more simple, efficient, and commercially desirable.

With these and other objects in view, as will become more apparent as the description proceeds, the invention consists in certain novel features of construction, combination, and arrangement of parts, as will be herein-after described and claimed.

For a complete understanding of my invention, reference is to be had to the following description and accompanying drawings, in which,

Figure 1 is a front elevation of an engine constructed in accordance with my invention, Fig. 2 is a vertical sectional view taken on the plane of line 2—2 of Fig. 1, Fig. 3 is a horizontal sectional view taken on the plane of line 3—3 of Fig. 2, Fig. 4 is a fragmentary sectional view taken on the plane of line 4—4 of Fig. 1, and, Fig. 5 is a detail perspective view of one of the valves.

Referring in detail to the drawings by numerals, 6 designates, generally, a two-cyl-

inder engine casting, 7 and 8 the working cylinders, and 9 the valve casing. A water jacket casing 10 surrounds the outer ends of the cylinders and the valve casing, and is provided with the filling and drain openings 60 11 and 12, respectively. The valve casing 9 is essentially cylindrical in shape, extends transversely across the front of the engine casting adjacent the outer ends of the cylinders, and communicates with said cylinders 65 by means of the ports 13 and 14, respectively. The valve casing is formed intermediate its ends with the intake opening 15 and adjacent each end with the exhaust openings 16 and 17. Upon reference to Fig. 2, it will 70 be seen that these openings are arcuately shaped and that the two exhaust openings are in the same quadrant with each other but in a different quadrant with respect to the intake opening. Removable cover plates 75 18 close the ends of the valve casing and carry the exhaust pipes 19 and 20, which communicate with the exhaust openings 16 and 17, respectively.

A valve shaft 21 extends longitudinally 80 through the valve chamber and has rigidly secured thereto the valves, generally designated 22 and 23, which control the flow of gases to and from the working cylinders 7 and 8, respectively. These valves are similar in construction with the exception of the fact that their ports, flanges, etc., extend in opposite or reverse directions. The valve 23 which is clearly shown in Fig. 5, comprises a hollow cylindrical shell or body 90 24, which is divided longitudinally into two compartments by means of the core 25, rib 26, and spiral flange 27. The core is somewhat shorter than the shell and is formed with the bore 28, through which the valve 95 shaft 21 is adapted to pass. The flange 27 may be considered as beginning at the outer end of the shell and rib 26 and running spirally around the core until it reaches the inner end of the shell. This construction divides said shell, as before stated, longitudinally into two compartments 29 and 30, which open upon opposite ends of the valve. The shell is formed in one quadrant with an intake opening 31 of a somewhat 100 triangular shape and tapering toward the outer end of the valve. This opening communicates with the compartment 29 and is formed with a straight forward wall 32 which extends longitudinally of the valve 110

shell, the inner end wall 33, the relatively short outer end wall 34, and a diagonal rear wall 35. The end walls extend parallel to the ends of the cylinder and form in junction with the front and rear walls, a somewhat triangular opening. The exhaust opening 36 is formed with the quadrant preceding that in which the intake opening is formed and communicates with the compartment 30. The exhaust opening has a straight forward wall which is parallel to the wall 32 and which is equal in length to the port 14 formed in the cylinder 8. The outer end wall of the exhaust opening is greater in length than the inner end wall, thus giving to the exhaust opening a somewhat triangular shape. The rear of the exhaust opening is formed with a diagonal wall 37 and a straight wall 38.

20 The valve 22 being of essentially the same construction as the valve just described, will not be described in detail. Its shell 39 is divided longitudinally into an exhaust compartment and an intake compartment, 25 said last mentioned compartment having its open end opposed to the open end of the compartment 29. The shell 39 is formed with intake and exhaust passages similar to those formed in the shell 24 and the valve 30 is so fixed upon the shaft 21 as to permit the cylinder 7 to exhaust as the gases are flowing into the cylinder 8.

It is to be understood that while I have shown my invention embodied in a two cylinder engine, I do not wish to be limited in this respect, but may employ my valve with an engine of one or more cylinders.

The inner ends of the valves revolve against a flange 40 and locking rings 41 are threaded into the ends of the valve chamber against the outer ends of the valves, thus holding the latter against longitudinal movement. The ends of the valves are annularly recessed to receive the rings 42, 45 which are loosely fitted within said recesses and which serve to keep the lubricant moving freely.

From the foregoing description in connection with the accompanying drawings, 50 it will be seen that my improved valves open the passages 13 and 14 suddenly and close said passages gradually. As the piston within the working cylinder 8 is reaching the end of the intake stroke, the diagonal wall 35 gradually closes the port 14 and it is to be noted that the inner end of this port is the last part of the same to be closed, therefore permitting the final volume of incoming gas to pursue the shortest possible course from the manifold through the intake port 15 into the cylinder. When the cylinder is ready to exhaust, the passage 14 opens quickly and the diagonal wall 37 gradually closes the port 14 from the inner to the outer end thereof so that the ex-

haust gases take the shortest possible path to the exhaust manifold.

It is to be understood that while I have shown and described the preferred construction of my improved valves, slight departures therefrom which would be apparent to anyone skilled in the art, may be made without departing from the spirit and scope of the invention.

Having thus described my invention, 75 what I claim is:—

1. In combination with a two cylinder internal combustion engine having an elongated port formed in each cylinder, a cylindrical valve casing formed around said ports and communicating with the interior of the cylinders by virtue thereof, the axis of the casing being parallel to the cylinder port, said casing being formed with an intake opening centrally of its ends and exhaust openings adjacent its ends, and a pair of rotary valves housed within the casing for individually controlling flow of gas into and from the cylinders, each valve comprising a cylindrical shell open at each end and divided longitudinally into an intake compartment and an exhaust compartment, 85 said compartments being closed at one end and opening upon opposite ends of the shell, the intake compartments being opposed to 90 one another and in communication with the intake opening of the valve casing, and the exhaust compartments being in communication with the exhaust openings of the valve casing, each shell being formed with a longitudinal port communicating with the intake compartment thereof and adapted to register with a cylinder port when the valve is rotated, said port having a front wall parallel to the axis of the valve casing and a rear wall inclined to the front wall whereby a quick opening of the cylinder port results, 95 said port being gradually closed toward the intake end of the valve, each shell being also formed with an opening communicating 100 with the exhaust compartment thereof and adapted to register with a cylinder port.

2. In combination with an internal combustion engine, cylinder formed with an elongated port, a valve casing formed around said port and paralleling the same, and a rotary valve housed within said casing having a cylindrical shell open at each end and divided longitudinally into an intake compartment and an exhaust compartment, 115 said compartments being closed at one end and opening upon opposite ends of the valve, the casing being formed with an intake port in continuous communication with the intake compartment of the valve and with an exhaust port in continuous communication with the exhaust compartment of the valve, the shell having a longitudinal port communicating with the intake opening of the valve and tapering toward the 120 125 130

inner end of said opening, the shell also having a longitudinal port communicating with the exhaust compartment of the valve and tapering toward the inner end 5 thereof, the forward walls of said openings paralleling the cylinder port, a rotation of the valve causing the openings to alternately register with said cylinder port.

3. In combination with a two cylinder internal combustion engine having a port formed in each cylinder, a cylindrical valve casing formed around said port parallel with the same, the casing being formed centrally of its ends with an intake opening and 15 adjacent its ends with exhaust openings, cover plates closing the ends of said valve casing, exhaust pipes carried by said plates,

a valve shaft journaled through the plate and running longitudinally of the valve casing, a pair of rotary valves rigid with said 20 shaft and designed to properly control the flow of gases into and from the engine cylinders, an annular flange formed on the interior of the valve casing centrally of its ends for engagement by the inner ends of 25 the valve, and locking rings threaded into the ends of the valve casing for engagement with the outer ends of the valve.

In testimony whereof I affix my signature in presence of two witnesses.

CHARLES R. SPENCER.
